GLOVE AND METHOD OF MAKING
THE SAMELouis Levine, Jersey City, N. J., assignor to Julius
Kayser & Co., New York, N. Y., a corporation
of New York

Application December 23, 1944, Serial No. 569,518

12 Claims. (Cl. 2—169)

1

My invention is a glove, and method of making the same, wherein trunk pieces of the digital sheaths are overlaid and bordered by edges of fourchettes forming ridges of substantially U-shape and preferably having termini spaced from the tips of the fingers and merging into the tip seams.

The raw margins of the fourchettes are preferably doubled, hemmed or welted so as to form finished, non-raveling edges having laps secured together and to the back finger pieces of the trunk by stitching having bights exposed on the right side of the glove, preferably in a single row, between the ridge-forming edge of the fourchette and the concealed raw edge of the finger back piece. There are thus formed decorative, lapped seams bordering and minimizing the visible width of the back finger pieces of the trunk.

By a lapped seam I mean a fold or line formed by sewing together pieces of material having their bodies laid right side up and projecting in opposite directions from the row of stitching attaching them together and with only their edge portions overlapped. By doubling back the margin of the superposed lapped material, as in a hem or welt, or by laying a cord between the body and under-folded margin of the superposed material, the height of the ridge formed may be accentuated.

The fourchettes are preferably connected with the front or palm finger pieces of the trunk, and the trunk's front and back finger pieces are connected together at their tips by a row of stitching having bights invisible from the right side of the glove and forming a plain, inconspicuous seam or inseam.

A glove so constructed tends to impart a slenderizing and tapering effect to the fingers and gracefulness to the tips thereof; provides smooth finger tips and finger fronts facilitating picking up and grasping objects without awkwardness; eliminates the exposure of raw edges and the raveling thereof, and may be made with a minimum number of rows of stitching and with a minimum amount of manipulation.

In constructing my improved glove, a continuous fourchette strip may be initially attached right side up to the right side of a trunk piece forming an end finger back and then, as part of a continuous operation, attached to the adjacent edge of the next finger. The fourchette strip is then looped loosely across two fingers and attached to the edge of the finger next to the opposite end finger and then, as part of a continuous operation, to such opposite end finger. The

2

fourchette strip is then cut and a new section attached, in a continuous operation, to the adjacent inner edges of the back inner finger pieces.

The glove blank is then turned wrong side out and the tips of the back and front finger pieces and the fourchettes and front finger pieces are seamed together by a continuous row of stitching forming a plain seam.

The characteristic features and advantages of my invention will further appear from the following description and the accompanying drawings in illustration thereof.

In the drawings, Fig. 1 is a plan view of an expanded glove embodying my invention; Fig. 2 is a diagrammatic, transverse sectional view on the line 2—2 of Fig. 1; Fig. 3 is a side view of a finger taken on the line 3—3 of Fig. 1; Fig. 4 is a plan view of the palm face of an expanded glove having the forefinger bent at right angles to the palm and the other fingers bent over against the palm; Fig. 5 is a perspective side view of the glove; Fig. 6 is a fragmentary enlarged view of the finger portion of a collapsed glove; Fig. 7 is an end view of the middle finger of the glove shown in Fig. 1; Fig. 8 is a transverse sectional view of the middle finger on the line 8—8 of Fig. 1; Fig. 9 is a somewhat diagrammatic perspective view of a glove trunk and fourchette strip and the sewing mechanism for combining them; Fig. 10 is a transverse sectional view taken on the line 10—10 of Fig. 9; Fig. 11 is a transverse sectional view taken on the line 11—11 of Fig. 9; Fig. 12 is a transverse sectional view similar to Fig. 11 but showing a welt cord being fed into the welt; Fig. 13 is a diagrammatic plan view illustrating the first step of the operation of attaching the fourchette to the trunk; Fig. 14 is a diagrammatic plan view illustrating the second step of attaching the fourchette to the trunk; Fig. 15 is a diagrammatic plan view illustrating a third step in attaching the fourchette to the trunk; Fig. 16 is a fragmentary plan view of the trunk with fourchettes attached to the back finger pieces; Fig. 17 is a somewhat perspective plan view of the trunk and attached fourchettes turned wrong-side-out; Fig. 18 is a diagrammatic view illustrating the first step in the attachment of a fourchette to the palm piece of the forefinger; Fig. 19 is a diagrammatic view illustrating the attachment of the trunk to one side of the palm piece of the middle finger; Fig. 20 is a fragmentary diagrammatic view illustrating the attachment of the trunk to the other side of the palm piece of the middle finger; Fig. 21 is a diagrammatic view illustrating the attachment of a fourchette to one edge of the palm piece of the

ring finger; Fig. 22 is a diagrammatic view illustrating the attachment of a fourchette to the other edge of the palm piece of the ring finger; Fig. 23 is a diagrammatic view illustrating the attachment of a fourchette to one side of the palm piece of the little finger; and Fig. 24 is a diagrammatic view illustrating the attachment of the side edges of the trunk.

Gloves embodying my invention may be made of any suitable material or combination thereof and for any desired purpose, but as an example I have shown in the drawings a woven fabric dress glove having a carpal portion 1 and a metacarpal portion 2 of any usual or desired construction and terminating in a digital portion comprising digit sheaths 3, 4, 5 and 6 embodying the novel features of my invention.

The digital sheaths 3, 4, 5 and 6 are composed of finger back pieces 7, 8, 9 and 10 integral with the back of the metacarpal portion, the finger front pieces 11, 12, 13 and 14 integral with the palm of the metacarpal portion, and the fourchettes 15, 16 and 17, comprising bifurcated members, forming distance pieces between the finger back and front pieces.

The fourchette 15 is connected with the finger pieces 7 and 8 by a continuous row of stitches 18 having bights exposed on the right side or outside of the glove. The stitches 18 pass through the body and doubled-under margin of the fourchette 15 and through the finger pieces 7 and 8 to form a lapped decorative seam 19 providing a substantially U-shaped ridge bordering and overlying the concealed, adjacent, raw edges of the finger pieces 7 and 8 and the juncture of their bases with one another and with the metacarpal portion 2.

The fourchette 16 is connected with the finger back pieces 8 and 9 by a continuous row of stitches 20 having bights exposed on the right side or outside of the glove. These stitches pass through the body and doubled-under margin of the fourchette 16 to form a lapped decorative seam 21 providing a substantially U-shaped ridge bordering and overlying the concealed, adjacent, raw edges of the finger pieces 8 and 9 and the juncture of their bases.

The fourchette 17 is connected with the finger back pieces 9 and 10 by a continuous row of stitches 22 having bights exposed on the outside or right side of the glove. These stitches pass through the body and doubled-under margin of the fourchette 17 and through the finger pieces 9 and 10 to form a lapped decorative seam 23 providing a substantially U-shaped ridge bordering and overlying the concealed, adjacent, raw edges of the finger pieces 9 and 10 and the juncture of their bases.

A continuous row of concealed stitching 24 connects the tips of the finger pieces 7 and 11, an overturned edge of the fourchette 15 with overturned edges of the finger pieces 11 and 12, the tips of the finger pieces 8 and 12, an overturned edge of the fourchette 16 with overturned edges of the finger pieces 12 and 13, the tips of the finger pieces 9 and 13, an overturned edge of the fourchette 17 with overturned edges of the finger pieces 13 and 14, the tips of the finger pieces 10 and 14, the overturned edges of the finger pieces 10 and 14, and overturned edges of the back and palm pieces of the meta-carpal and carpal portions 2 and 1.

This concealed stitching forms a continuous plain seam 25; that is, a seam in which the bodies of the joined members are overlapped and lie right-side to right-side during stitching so that

when the joined members are turned right-side out the bights of the stitching and the raw edges are concealed and the seam is relatively inconspicuous.

It will be noted that the substantially U-shaped ridges formed by the overlapping welted edges of the fourchettes 15, 16 and 17 narrow the visible expanse of the back pieces 7, 8, 9 and 10 and may be merged into the plain seam 25 at points spaced from the extreme tips of the digital sheaths so as to impart a slenderizing and tapering effect to the fingers by reason of the tapering of the extremities of the fourchettes and the narrowing of the exposed areas of the finger back pieces and leave substantially unobstructed nail covering sections at the ends of the fingers.

To produce the glove of my invention efficiently and economically, a trunk A is cut in a single piece and a thumb sheath 26 set therein, preferably by a lapped seam.

The fourchettes are formed from a narrow strip of tape or raw-edged material 27 which may be pre-folded along one edge, but which is preferably fed flat from a continuous source of supply, such as a roll 28, to a conventional hammer or folder 29 attached to or forming a part of a conventional foot 30 of a sewing machine having a conventional reciprocating needle 31. As the strip 27 is automatically fed through the folder 29, an edge thereof is turned under, as shown in Fig. 11, and, if desired, a cord 32 may be simultaneously fed between the body of the strip 27 and its underturned edge so as to provide a corded welt instead of a plain welt, as in Fig. 12.

The trunk A is advanced right-side-up to the sewing machine so that the edge of the forefinger back piece 7 is advanced beneath the foot 30 and there overlaid with the underturned margin of the strip 27, whose body section is right-side-up and extends away from the body of the finger piece 7. The trunk is bent, as shown in Fig. 13, to align the adjacent edge of the middle finger back 8 with the edge of the forefinger back 7 and the strip 27 is stitched by the row of stitching 18 to the aligned edges of the finger pieces 7 and 8 in a substantially continuous sewing operation.

A section 33 of the strip 27 is left slack to permit the trunk A to be moved so as to bring the outer end of an edge of the ring-finger piece 9 under the foot 30, and the trunk is bent to effect the alignment of an edge of the little finger piece 10 with the edge of the ring-finger piece 9. The strip 27 is then stitched by the stitching 22 to the consecutive, aligned edges of the finger pieces 9 and 10, and the strip 27 is then twice cut transversely to free the trunk therefrom and to sever the section 33.

The trunk is then moved to bring the unsewn edge of the middle finger piece 8 beneath the foot and bent to align the unsewn edge of the ring-finger piece 9 therewith. The strip 27 is then attached by the row of stitching 20 to the consecutive, aligned edges of the finger pieces 8 and 9. The strip 27 is again cut transversely to free the trunk.

As a result of these operations, and by a single passage of the parts through the sewing machine, the trunk has fixed thereto by lapped seams the fourchettes 15, 16 and 17 with the right-side of the trunk and of the fourchettes up, as shown in Fig. 16.

The trunk is then folded lengthwise, as shown in Fig. 17, so as to expose the wrong side of the trunk fabric with the palm section and front

finger pieces 11, 12, 13 and 14 up. With the trunk in this position, the tips of the finger pieces 7 and 11 are aligned and fed to the sewing machine, where they are attached together by an initial section of the row of stitching 24 to form the initial portion of the plain seam 25. Such tips having been sewn, and without disengaging them from the needle, the edge of the finger piece 11 is stretched diagonally across the section of the fourchette 15 attached to the finger piece 7, so that the edge of the finger piece 11 adjacent to its juncture with the metacarpal portion 2 coincides with the free edge of the fourchette 15. The diagonally disposed edge of the finger piece 11 is then sewed to the fourchette 15 by a continuation of the row of stitching 24, thus forming a continuation of the plain seam 25.

While still on the needle, the trunk is turned end for end, as shown in Fig. 19, and the tips of the finger pieces 8 and 12 are aligned. This causes the edge of the finger piece 12 to extend diagonally across the section of the trunk 15 secured to the finger piece 8, and it is stitched in this position and the tips of the finger pieces 12 and 8 are stitched together by a continuation of the row of stitching 24, thereby forming a further continuation of the plain seam 25.

The trunk is then turned end for end, without removal from the needle, and the unsewn edge of the finger piece 12 is stretched diagonally across the fourchette section 16 secured to the finger piece 8, as shown in Fig. 20, so that the edge of the finger piece 12 at its juncture with the metacarpal portion 2 is coincident with the edge of such fourchette section 16. Such edge of the finger piece 12 is attached in such position to the fourchette section 16 by a continuation of the row of stitching 24, forming a further extension of the plain seam 25.

Without removal from the needle, the trunk is again turned end for end, as shown in Fig. 21, the tips of the finger pieces 9 and 13 are aligned with one another. This causes the edge of the finger piece 13 to extend diagonally across the section of the fourchette 16 attached to the finger piece 9 and it is stitched in such position and the tips of the finger pieces 9 and 13 are stitched together by a continuation of the row of stitching 24 to form a further extension of the plain seam 25.

The trunk is again turned end for end, without removal from the needle, and the unsewn edge of the finger piece 13 is stretched diagonally across the section of the fourchette 17 attached to the finger piece 9, as shown in Fig. 22, so that the edge of the finger piece 13 adjacent its juncture with the metacarpal portion 2 is coincident with the edge of the fourchette section 17. The finger piece 13 is stitched in such position by a continuation of the row of stitching 24 and forms a further extension of the plain seam 25.

The trunk is then turned end for end, as shown in Fig. 23, and the tips of the little finger pieces 10 and 14 are aligned with one another. This causes the edge of the finger piece 14 to extend diagonally across the section of the fourchette 17 attached to the finger piece 10. The edge of the finger piece 14 is stitched in such position to the fourchette 17 and the tips of the finger pieces 10 and 14 are stitched together by a continuation of the row of stitching 24.

The trunk is then again turned end for end, without removal from the needle, and the edges of the finger pieces 10 and 14 and the edges of the metacarpal and carpal sections 2 and 1 are

aligned as shown in Fig. 24 and stitched together by a continuation of the row of stitching 24 to complete the seam 25.

It will, of course, be understood that in passing from one finger piece to another the rows of stitching 18, 20, 22 and 24 will extend to a small extent into the metacarpal portion 2 at the bases of the finger pieces and secure the apexes of the fourchettes 15, 16 and 17 thereto.

The excess portions of the fourchettes projecting laterally beyond the seam 25 are trimmed off, the glove is turned right-side out and hemmed at the wrist or otherwise finished or decorated with points, if required.

Having described my invention, I claim:

1. A glove having digital sheaths comprising fourchettes and front and back trunk finger pieces, and stitching seaming said finger pieces together at their tips, said fourchettes having edges overlying and bordering and directly engaging said finger pieces close to the margins thereof and forming substantially U-shaped ridges merging into said tip seams, said fourchettes partially concealing the widths of the back trunks of the sheaths and the seamed front and back trunks forming smooth finger tips at the apexes thereof.

2. A glove having digital sheaths comprising trunk finger pieces having concealed longitudinal edges and fourchettes having doubled margins forming laps secured together and to said finger pieces by a single row of stitches only, said stitches having bights exposed on the right side of the glove and forming rows between the exposed bent edges of the fourchettes and concealed edges of the finger pieces.

3. A glove including back and front finger pieces and fourchettes having welted edges bordering and overlying and reducing the apparent width of the right sides of the back finger pieces aforesaid, said welted edges and back finger pieces directly engaging one another and secured by a single seam, and said fourchettes and front finger pieces being secured together by inseams.

4. A glove including back finger pieces and fourchettes having hemmed margins bordering and overlying and reducing the apparent width of the right sides of finger pieces aforesaid, the hemmed margins having inturned pieces directly engaging the finger pieces.

5. A glove including back finger pieces and fourchettes having hemmed edges bordering and overlying and directly engaging outer surfaces of finger pieces aforesaid close to the margins thereof, and rows of stitching having external bights extending along the fourchette edges, and the overlying fourchette edges reducing the visible width of the back finger pieces.

6. A glove including back finger pieces and palm finger pieces having their tips connected by inseams and fourchettes having welted edges bordering and overlying and reducing the apparent widths of the outer surfaces of finger backs aforesaid below said inseams, rows of stitching having external bights extending along the welted edges of said fourchettes and connecting them with back finger pieces aforesaid to form lapped seams, said fourchettes being connected with palm finger pieces aforesaid by inseams.

7. A glove having digital sheaths comprising trunk back and front finger pieces and fourchettes having doubled edges overlying and bordering and reducing the apparent widths of said back finger pieces, stitches having bights exposed on the right side of the glove and connecting the doubled edge

of each fourchette with adjacent edges of adjoining back finger pieces and forming a lapped seam of substantially U-shape having legs of less length than the fingers, and a continuous seam connecting tips of complementary finger pieces and front finger pieces with said fourchettes.

8. In the manufacture of a glove from a fourchette strip and a trunk having back finger pieces and front finger pieces, the steps which include seaming a fourchette strip to an edge of an end finger piece, then to the adjacent edge of an adjoining finger piece, then to the edge of a finger piece adjoining the opposite end finger piece and then to said last named end finger piece.

9. In the manufacture of a glove from a fourchette strip and a trunk having back finger pieces and front finger pieces, the steps which include stitching a fourchette strip along the edge of the back forefinger piece, then along the edge of the back middle finger piece, then along the edge of the back ring finger piece; then along the edge of the back little finger piece, then along the other edge of the back middle finger piece and then along the other edge of the back ring finger piece.

10. In the manufacture of a glove from fourchettes and a trunk having back finger pieces and palm finger pieces, the steps which include seaming fourchettes right-side-up to the right sides of the back finger pieces, folding the trunk and then stitching the palm finger pieces wrong-side-up to the fourchettes right-side-up.

11. In the manufacture of a glove from four-

chettes and a trunk having back finger pieces and palm finger pieces, the steps which include overlapping doubled back edges of fourchette pieces over the right side of back finger pieces and stitching them together, with the right side of the fourchette pieces and back finger pieces upward, to form a lapped seam.

12. In the manufacture of a glove from a fourchette strip of substantially uniform width and a trunk having back finger pieces and front finger pieces, the steps which include turning an edge of the fourchette strip and stitching the turned edge to said back finger pieces to form fourchettes, and stitching the edges of the front finger pieces substantially diagonally across said fourchettes.
